UNITED STATES PATENT OFFICE.

JAMES W. MALOY, OF SOMERVILLE, ASSIGNOR, BY MESNE ASSIGNMENTS,
TO THE AMERICAN MARBLE CUTTING COMPANY, OF BOSTON, MASS.

STONE-CUTTER HEAD.

SPECIFICATION forming part of Letters Patent No. 334,595, dated January 19, 1886.

Application filed December 15, 1884. Renewed November 27, 1885. Serial No. 184,127. (No model.)

To all whom it may concern:

Be it known that I, JAMES W. MALOY, a citizen of the United States, and a resident of Somerville, in the county of Middlesex and 5 State of Massachusetts, have invented certain new and useful Improvements in Stone-Cutter Heads, of which the following is a specification.

My invention relates to that class of cutter-heads used for cutting stone; and it consists of a hub provided with lateral studs or bearings, and with disk-cutters revolving on said bearings, all constructed and arranged, as fully set forth hereinafter, so as to cut the stone 15 without chipping the edges, secure increased durability of the cutters, thoroughly lubricate the same, and generally improve the operation of the device.

In the drawings, Figure 1 is a sectional elevation of my improved cutter-head. Fig. 2 is an inverted plan view. Fig. 3 is a diagram illustrating the course of the cutting-edges. Figs. 4 and 5 are detached views illustrating the channel-bearing surfaces. Figs. 6 and 7 illustrate modifications. Fig. 8 illustrates the operation of a cutter of ordinary construction.

A represents the hub of a cutter-head, which is threaded or otherwise adapted for attachment to the driving-spindle of the machine, 30 and which is provided with an angular projection, a, having three or more faces, from each of which extends at right angles a stud, c, supporting the revolving circular cutters B, each of which consists of one or more flat bevel-edged disks, b b b, clamped or otherwise secured together so as to be readily detachable, and so as to permit each cutter to be built up of a series of disks of any desired 35 thickness or varying thicknesses, and of such 40 number as to form a cutter of the required dimensions.

In the drawings, the projection a is shown as having four equal sides, and it will be seen that the studs c are set nearest the forward 45 edge of each side, instead of being upon a radial line, so as to leave a clearance between the rear edge of each cutter and the edge of the material cut by the forward edge of the said cutter. When the projection has three 50 or any other number of sides, the studs are

likewise arranged out of center to secure the requisite clearance, as illustrated in Fig. 6.

Each stud c is arranged at right angles to the axis of the hub, so that the cutters will stand at right angles to the face of the stone. 55 This insures a direct downward cut and prevents the chipping of the stone at the edges of the opening, which results when the cutters are set flaringly outward, in the usual manner, as illustrated in Fig. 8. This result may be secured by arranging the cutters either vertically, as described, or converging toward the lower edges, as illustrated in Fig. 7, the stone in either case chipping ahead of the cutters or toward the center, instead of radially outward. 60 65

In order to cut or score the stone upon circular lines in close proximity without of necessity using thin cutting-disks b or fine or closely-arranged cutting-edges, I set each cutter so that the cutting-edge x of each disk will travel in a path nearer to or farther from the center than the edges of the following disks, so that while the said edges in each cutter are sufficiently far apart to permit heavy and durable disks to be used, the scores a b c d, made by the following edges of the various cutters, will be close together, as shown in the diagram, Fig. 3, thereby greatly facilitating the cutting, reducing the liability to chip, and 70 75 avoiding the rapid wear which results when the cutting-edges upon each cutter are in close proximity.

Each cutter may turn directly upon the stud c. I prefer, however, to mount the several 85 disks composing each cutter upon a sleeve, D, provided with a shoulder, y, and with a threaded end receiving a nut, E, by which the disks are clamped firmly in place upon the sleeve which rotates upon the stud. 90

In this class of machines the access of fine marble-dust to the bearings of the cutters results in the rapid wear of the said bearings and in the drumming up of the oil used for lubricating the same. To prevent this, I inclose the 95 end of the sleeve D in a tubular guard, I, which extends from the face of the projections a to the adjacent side of the cutter, forming an oil-chamber, w, surrounding the end of the sleeve, in which the lubricant may be put when the 100

cutter is mounted upon its stud, and where it is confined, so as to flow readily to the bearing-surfaces without permitting the access of dust.

To facilitate the passage of the lubricant to the stud, I form one or more notches, *i*, in the end of the sleeve *D*, and to secure a better lubrication than would result from the bearing of the sleeve against the side of the projection *a*, I mount a disk, *J*, upon the stud and secure to a second disk, *K*, across the guard-tube *I*, extending between the end of the sleeve *D* and the disk *J*, and I form recesses *s* in the face of the disk *J*, so that the sleeve has a bearing against the face of the disk *K*, and the latter has a bearing against the face of the disk *J*, and these parts are all inclosed by the guard-tube *I*, within which the lubricating material is confined in contact with all the faces. The sleeve *D* is held in position upon the stud *c* by a nut, *N*, screwing upon the threaded end of the stud and bearing upon an intervening washer.

I do not here claim a head carrying railroad studs and disks converging toward their lower edges, as this is claimed in my application filed December 15, 1884, No. 150,416.

Without limiting myself to the precise arrangement of parts shown, I claim—

1. The combination, in a stone-cutter head, of a hub carrying a series of studs projected at right angles to the axis of the hub and cutter-disks mounted upon said studs, parallel to the axis of the hub, substantially as set forth.
2. The combination, in a cutter-head, of a hub provided with laterally-projecting studs carrying disk-cutters at their outer ends, each of said studs being arranged with the axis of the disk forward of the axis of the hub, substantially as set forth.

3. The combination, in a cutter-head, of a hub and studs extending laterally from the axis thereof and carrying circular cutters arranged at different distances from the axis of the hub and at the outer ends of the studs, so that the cutting-edges of each cutter will travel upon circular paths parallel to but differing from those of all the other cutters, substantially as set forth.

4. The combination of the cutter-head having an angular extension, *a*, a stud projecting laterally from each side face of said extension, 50 a sleeve revolving upon said stud and carrying the cutter, and guard *I*, inclosing the space between the cutter and the face of the hub and forming a chamber to receive the lubricating material, substantially as specified.

5. The combination of the cutter-head, the hub, stud projecting laterally from the hub, cutters mounted on the stud, a sleeve also mounted upon the stud and provided with grooves *i*, and inclosing-guard *I*, substantially 60 as set forth.

6. The combination, with the cutter-head, of the hub, a stud projecting laterally from the hub, a sleeve mounted on the stud, and cutters carried on the stud, channel disk *J*, embracing 65 the stud, tubular guard *I*, and intervening disk, *K*, substantially as set forth.

In testimony whereof I have signed my name to this specification in the presence of two subscribing witnesses.

JAMES W. MALOY.

Witnesses:

GEORGE R. EAGER,
CHAS. M. TILLINGHAST.

Correction in Letters Patent No. 334,595.

It is hereby certified that Letters Patent No. 334,595, granted January 19, 1886, upon the application of James W. Maloy, of Boston, Massachusetts, for an improvement in "Stone-Cutter Heads," was erroneously issued to "The American Marble Cutting Company;" that said Letters Patent should have been issued to *The American Marble Cutting Company of Maine, its principal place of business being in Boston, Massachusetts*; that this correction has been made in the records of the case in the Patent Office, and that the said Letters Patent should be read to conform thereto.

Signed, countersigned, and sealed this 3d day of August, A. D. 1886.

[SEAL.]

H. L. MULDROW,
Acting Secretary of the Interior.
